UNITED STATES PATENT OFFICE.

GEORGE M. BECK, OF LEBANON, INDIANA.

WASHING-MACHINE.

SPECIFICATION forming part of Letters Patent No. 412,719, dated October 15, 1889.

Application filed January 29, 1889. Serial No. 297,904. (No model.)

To all whom it may concern:

Be it known that I, GEORGE M. BECK, a citizen of the United States, residing at Lebanon, in the county of Boone and State of Indiana, have invented certain new and useful Improvements in Washing-Machines; and I do hereby declare the following to be a full, clear, and exact description of the invention, such as will enable others skilled in the art to which it appertains to make and use the same.

This invention relates to washing-machines of the class shown and described in a separate application filed May 10, 1888, Serial No. 15 273,483; and it consists in the novel construction and combination of the parts hereinafter fully described and claimed, which are improvements upon the washing-machine described in the aforesaid application.

In the drawings, Figure 1 is a vertical longitudinal section through the washing-machine tub and the rubber. Fig. 2 is a plan view from below of the rubber lid. Fig. 3 is a detail side view of a portion of the rubber, 20 showing the attachment of the handles. Fig. 4 is a detail plan view of the bracket, to which the rubber and drip-board cranks are pivoted. Fig. 5 is a plan view from below of the drip-board. Fig. 6 is a side view of the 25 concave wash-board. Fig. 7 is a plan view of the same from below. Fig. 8 is a perspective view showing the upper end of one of the side plates of the wash-board. Fig. 9 shows two simple modifications in the means for securing the cover to the rubber pivot-rod. Fig. 10 is an enlarged cross-section taken on line α α in Fig. 5.

A is the wash-tub, provided with the sheet-metal bottom A', secured to the sides of the 30 tub. A slanting end board a is secured between the sides at one end, and a' is the wringer-board, also secured between the sides at the other end of the tub.

B is the removable concave wash-board 40 provided with a series of slats b.

B' are the curved side plates, to which the ends of the slats are secured by nails or screws b'.

C is a slanting end piece at the wringer-board end of the wash-board, and C' are enlargements of the side plates B', for support-

ing the end piece C. A flange c is bent around at one edge of each enlargement C', for further supporting the end piece C and the slat which comes next to it in the series, 55 and c' are small flanges at the extreme ends of the side plates, which are bent over on top of the end piece C.

D are lugs projecting from the ends of the flanges c, and D' are diagonal cross stays secured to lugs D and extending under the slats to the diagonally-opposite corners of the wash-board. Small flanges d are formed upon the ends of the cross-stays and are bent over upon the end slat, and d' are nails or 60 screws which secure each slat to the cross-stays. The arrangement of the stays, which cross each other diagonally, gives to the slats a large amount of lateral support and at the points where support is most needed, and 65 thereby enables the slats to withstand the continued strain which comes upon them when in use without springing or breaking.

E is a hook pivoted to the top of end piece C, for engaging with the eye E', projecting 70 from the wringer-board. One end of the wringer-board abuts against the lower end of board a, and the other end is secured by the hook E.

e is a vertical groove in the end piece C 80 and the first slat, which clears the eye E' and permits the wash-board to be removed from the tub as often as desired.

F is the drip-board, provided with the groove f, and F' is the crank which pivots the 85 said board to brackets upon the sides of the tub. The central rod portion of crank F' is placed in the groove f, and is retained therein by the three plates f'. These plates f' are secured at one end to the drip-board, and 90 have their other ends bent into the groove f, over the crank-rod. One plate f' is secured in the middle of the drip-board, and the other two plates f' are secured at the ends of the drip-board and upon the opposite side of the 95 crank-rod from the said central plate. This arrangement retains the crank-rod in the groove and allows the wood to swell and shrink without binding the rod, and it also provides an ample curved surface for the rod 100 to rub against. The wooden sides of the groove can swell without pinching the rod

between them, and when the bottom of the groove swells, or when the board F becomes warped, twisted, or otherwise bent out of line by the alternate wettings and dryings to 5 which it is subjected, the ends of plates f' spring back slightly and accommodate themselves to the rod, allowing the board to turn freely on said rod. The extreme ends of crank F are pivoted in the lugs g, which project downwardly inside the tub from one end 10 of the plates G, which are secured on the top of the sides of the tub by two or more nails or screws g'.

G' are downwardly-projecting lugs upon 15 the other ends of plates G, outside the tub, for the ends of the rubber-crank to pivot in. It will be seen that the bracket G' serves the double purpose of pivoting both cranks. It also braces the sides of the tub and fixes the 20 exact distance of the crank-pivots apart from each other in putting the machine together.

H is the rubber, provided with a series of slats H', and h is the rod upon which the said rubber is pivoted. This rod is provided with 25 the cranks h', the extreme ends of which are pivoted in the lugs G' of plates G, as before described.

I are plates secured to the sides of the rubber and journaled upon the rod h, so that the 30 rubber may rock freely.

I' are curved slots in extensions i of plates I, above the top of the rubber, and i' are ledges which rest upon the top of the sides of the rubber.

35 J are the handles connected by the handle-bar j.

J' are pins which pivot the lower ends of the handles to the extensions i of plates I, and j' are screws which pass through the 40 slots I' and engage with the handles. The handles can be set at any angle and secured there by the screws j'. This permits the 45 handles to be adjusted to suit the convenience of the person working the machine, and allows them to be lowered, so as to make the machine more compact for shipment.

K is the removable lid which fits loosely 50 within the top of the rubber, and is secured to and supported by the rod h. This lid keeps in most of the steam and prevents the water from splashing up. The rubber is rocked without moving the lid; but the lid rises with any rising motion of the rubber and of the rod upon which the rubber is pivoted. The thin metallic lid K slopes downwardly from the center in both directions, so 55 as to let water run off it, and it is provided with two flat-bottomed wooden side pieces L, firmly secured to it. The ends of the lid are further stiffened by the beads or flanges k. The side pieces L have notches l for the rod h to rest in, and M are flat springs secured 60 to the sides and provided with downwardly-bent ends m. The rod h has flat places m' upon it, which engage with the springs, so 65 that the rod is retained in the notches l and the lid is kept horizontal. The lid is re-

moved by using sufficient force to cause the rod to press back the springs, and the bent ends m allow the springs to be slid back under the rod when it is desired to replace the lid. The springs M can be made of round instead of flat steel, if desired, and holes can be formed through the rod h for the springs to pass through; or brackets can be secured to the rod and provided with holes or flat places for the springs to engage with, so as to connect the lid to the rod h and cause the lid to preserve its horizontal position while the rubber is being worked back and forth. 80

What I claim is—

1. The combination, with the curved side plates of the wash-board having the enlargements C' and the lugs D at one end, of the parallel slats secured between the side plates, 85 with their ends abutting against the sides of said plates, the slanting end piece secured between the said enlargements, and the diagonally-crossed stays secured to the underside of each of the slats and to lugs D, substantially 90 as and for the purpose set forth.

2. In a washing-machine, the combination, with the drip-board provided with a groove, of the rod pivoted in the said groove, a plate f' in the middle of the drip-board, and two 95 similar plates at the ends of the said board upon the opposite side of the crank-rod from the central plate, each of the said plates having one end secured to the drip-board and the other end bent into the groove over the 100 said rod for retaining it in position, substantially as set forth.

3. The combination, with a washing-machine tub, of the plates G, secured upon the top of the sides of the tub and provided with 105 the downwardly-projecting lugs g and G' at the opposite ends of the said plates and inside and outside the tub respectively, each lug being provided with a pivot-hole, substantially as and for the purpose set forth. 110

4. The combination, with the wash-tub and the pivot-rod h, supported by the tub, of the reciprocating rubber, the plates secured to the sides of the rubber and journaled upon the said pivot-rod and provided with the 115 ledges i', resting on the top of the rubber, and the extensions i above the rubber, having the curved slots I' in them, the handles pivoted to said plates between the curved slots and the pivot-rod holes, and the screws passing through said curved slots and adjustably connecting the handles to the said plates, substantially as set forth. 120

5. The combination, with a reciprocating rubber, of a pivot-rod, a lid closing the top of 125 the rubber, and a connecting device—such as a clip—for attaching the lid to the pivot-rod and retaining said lid in a horizontal position when the rubber is moved back and forth, substantially as set forth.

6. The combination, with a reciprocating open-topped rubber, of a pivot-rod for the rubber, a removable non-reciprocating lid closing the top of the rubber when in its cen- 130

tral position, and spring-clips rigidly secured to the lid at one end, with their free ends engaging with the pivot-rod, for connecting the lid to the said pivot-rod, substantially as set forth.

5 7. The combination, with a reciprocating open-topped rubber, of a pivot-rod for the rubber provided with flat places on its lower side, a lid fitting inside the top of the rubber, and the springs secured to the lid and provided with downwardly-bent ends and with horizontal portions bearing against the said flat places on the pivot-rod, substantially as and for the purpose set forth.

15 8. The combination, with a reciprocating

open-topped rubber, of a pivot-rod for the rubber, a removable sheet-metal lid sloping downwardly at each end and provided with flat-bottomed sides having central notches fitting over the pivot-rod, and springs secured 20 to the said side pieces of the lid and retaining the pivot-rod in the said notches, substantially as and for the purpose set forth.

In testimony whereof I affix my signature in presence of two witnesses.

GEORGE M. BECK.
